UNITED STATES PATENT OFFICE.

THOMAS B. LASHAR, OF BRIDGEPORT, CONNECTICUT, ASSIGNOR TO INTERNATIONAL SILVER COMPANY, OF MERIDEN, CONNECTICUT, A CORPORATION OF NEW JERSEY.

DESIGN FOR A HANDLE FOR FORKS, SPOONS, OR SIMILAR ARTICLES.

49,033.

Specification for Design.

Patented May 9, 1916.

Application filed March 11, 1916. Serial No. 83,667. Term of patent 7 years.

To all whom it may concern:

Be it known that I, THOMAS B. LASHAR, a citizen of the United States, residing at Bridgeport, county of Fairfield, State of Connecticut, have invented a new, original, and ornamental Design for a Handle for Forks, Spoons, or Similar Articles, of which the following is a specification, reference being had to the accompanying drawing, forming part thereof.

In the drawing, Figure 1 is a representa-

tion of a fork embodying my novel design with the outline of a spoon indicated by dotted lines, and Fig. 2 is a perspective of the tip of the handle.

What I claim is:—

The ornamental design for a handle for forks, spoons, or similar articles, substantially as shown.

In testimony whereof I affix my signature.

THOMAS B. LASHAR.
